GLOVE

Paul A. Chanut, New York, N. Y., assignor to
 Steinberger Bros. Glove Corporation, New
 York, N. Y., a corporation of California

Application March 16, 1934, Serial No. 715,989

8 Claims. (Cl. 2—162)

This invention relates to an improved glove and has for an object to provide an improved construction wherein a hand including fingers and a thumb are made in any desired form or conventional style, but the remaining parts of the glove are made to present a gauntlet formation with means for bending or setting the parts in different desired configurations.

Another object of the present invention is to provide a glove having at the cuff or gauntlet end one or more reinforced hems with the reinforcement so formed as to be deformed and remain in the deformed position until positively moved to another position.

15 An additional object is to provide in a glove a deformable structure at the cuff end of the glove, this structure including a ring or ornament associated therewith.

20 A further object, more specifically, is to provide in a glove a deformable member carried by the cuff at some point between the thumb and the end of the cuff for holding the parts in differently formed positions which may present ornamental formations or may present a constriction at or 25 near the wrist portion of the glove.

In the accompanying drawings—

Figure 1 is an elevation of a glove constructed according to the present invention;

Figure 2 is an enlarged side view of the hem member shown in Figure 1, the same being on an enlarged scale with certain parts broken away;

Figure 3 is a sectional view through Figure 2 on the line 3—3, the same being on an enlarged scale;

Figure 4 is an end view of the glove shown in Figure 1, looking at the glove from the cuff end, and with the hem and associated parts deformed to present a peculiar and pleasing appearance;

Figure 5 is a perspective view of a glove embodying certain features of the invention, and illustrating the same on a hand;

Figure 6 is a view similar to the lower part of Figure 1 but disclosing a slightly modified construction;

Figure 7 is a sectional view through Figure 6 on the line 7—7, the same being on an enlarged scale;

Figure 8 is a view similar to Figure 1 but showing the back of the glove and disclosing a modified structure;

Figure 9 is a view similar to Figure 1 but showing a modified form of the invention;

Figure 10 is a fragmentary sectional view through Figure 9 on the line 10—10, the same being on an enlarged scale;

55 Figure 11 is a view similar to Figure 1 except

that it is shown in place on an arm and illustrating a slightly modified construction;

Figure 12 is a sectional view through the glove shown in Figure 11, the section being taken on the line 12—12 of Figure 11;

Figure 13 is a view similar to Figure 1 except that it illustrates the back of the glove and also illustrates a slightly modified construction to that shown in Figure 1;

Figure 14 is an enlarged elevation of the ornamental member forming part of the glove shown in Figure 15;

Figure 15 is a sectional view through Figure 14 on the line 15—15.

Referring to the accompanying drawings by 70 numeral, 1 indicates a body of a glove having any desired form of fingers 2 and a thumb 3. The hand 1 of the glove merges into what may be termed a cuff or gauntlet 4. As shown in Fig. 1, the cuff flares in a desirable manner, and in 75 order to maintain this flare even throughout there is provided a reinforced stitched hem structure 5. The hem structure, as shown in Figs. 2 and 3, includes the hem 6, having a filling 7 of fibrous material, a bendable strip 8 formed with a fabric 80 coating, and a pair of wire inserts 9, said inserts extending for the full length of the strip 8, which strip also extends for the full length of the filling 7. The hem 6 is filled by the members 7 and 8 so that it is maintained tight and presents a rounded bead formation at the end of the cuff 4. This rounded bead formation may be bent to present a circular formation, or various other odd formations, for instance, the formation shown in Fig. 4. The wearer may bend the wire 9 85 at any time, i. e., either when the glove is not in use or when it is being worn.

Under some circumstances instead of having a single hem structure, there may be provided the bead structures 10 and 11 as shown in Fig. 6. 95 As a matter of fact, any desired number of bead structures may be used, each structure being of the construction shown in Figs. 2 and 3, whereby it may be readily bent to present different configurations which may be ornamental or may merely be arranged to hold it in certain desired positions.

In Fig. 2 a section through the structure shown in Fig. 6 is illustrated wherein the beads 10 and 11 are formed from an extension 12 of the cuff 4, 105 said extension being looped over the filling members and also over the members 8 and held in two tubular formations by the rows of stitching 13 and 14.

In Fig. 8 a further form of the invention is 110

shown wherein the bead 5' is provided with extensions 15 and 16 at the edge of the cuff 17. This permits other forms of adjustment for the respective parts, and by reason of the bendable feature of member 8 which is used in this form of the invention, a tight fitting glove structure may be provided or a loose fitting one as preferred.

In Fig. 5 the same structure is shown as in Fig. 1 except that there is provided an ornament 18 stitched in place, said ornament including an ornamental covering within which are arranged bendable wires which hold the ornament in position as shown in Fig. 5, or in any other position to which it may be moved. It is, of course, understood that various detailed ornamental members may be used, but in all instances there is a covering structure and within the covering structure are the supporting bendable wires as illustrated by the member 8 in Fig. 3.

Instead of having a bead as shown by the member 5 and also members 10 and 11, a variation may be provided as shown in Fig. 9, wherein there is a zone 19 spaced from the end 20, said zone carrying three bendable wires 21, though a greater or less number could be used without departing from the spirit of the invention. Each of these bendable wires is covered with a piece of fabric and rows of stitching are provided for holding the fabric just mentioned to the glove structure. This forms a slight corrugation which presents an ornamental appearance in addition to the useful effect. As illustrated in Fig. 10, the size is exaggerated in order to show the detailed structure.

In Figs. 11 and 12 a further form of the invention is shown wherein a glove 1 is provided at the wrist portion 22 with a zone 23 similar to zone 19 in Figs. 9 and 10. This zone 20 is preferably positioned exactly at the smallest part of the wrist, so that after the glove is placed in position on the hand the wrist portion may be bent over at 24 whereby the glove will snugly fit the wrist and hand but will loosely fit the remaining part of the arm, thus giving a slender appearance to the wrist and a pleasing appearance to the cuff or gauntlet portion.

In Figs. 13 to 15, inclusive, a glove 25 is disclosed, the same being similar to the glove shown in Fig. 11 except that it does not have the zone 23. Also the glove 25 is different in that it has an ornamental member 26 at a desired point, said ornamental member being in the form of a covering 27 and a wire frame 28, said wire frame being bendable into different shapes whereby the appearance of the ornament may be changed when desired. This ornament is held in place in any suitable manner, preferably by suitable stitching extending through the cover 27 and part of the glove 25.

I claim:

1. A glove of the character described, including a plurality of settable wires connected to the glove near the end opposite the fingers, certain parts of the glove forming a plurality of encircling tunnels for independently covering said wires.

2. A glove of the character described, including a cuff or gauntlet structure, said cuff or gauntlet structure having a hem, a resilient fibrous structure partly filling said hem, and a bendable settable structure arranged within the hem adjacent said fibrous filling and with said fibrous filling completely filling the hem so that it will present a bead, said bendable settable structure comprising a plurality of settable wires arranged in parallelism and a fibrous covering encircling both wires, said hem with its filling forming an encircling bead for the end of the glove, said encircling bead being adapted to be distorted whenever desired to present different configurations.

3. A glove of the character described, including a cuff provided with a folded over end producing a hem, lines of stitching in said hem producing a plurality of tunnels, and separate filling means for said tunnels, each filling means including a resilient filling core and a settable wire structure, said tunnels with their filling structures presenting parallel beads at the end of the glove.

4. A glove of the character described including a cuff having a slit in the back thereof, means forming a hem extending around the open end of the glove and the edges of said slit, and a filling for said hem including a resilient filling member of fibrous material and a settable wire whereby the hem will present a rounded bendable bead capable of remaining in different positions.

5. A glove of the character described, including a cuff provided with a folded over portion producing a hem, a plurality of lines of stitching dividing said hem into a plurality of tunnels, and a settable wire positioned in each tunnel.

6. A glove of the character described, including a glove body having thumb, fingers and a hand, the hand merging into a cuff or gauntlet, and a folded over edge portion at the cuff, a line of stitching forming a hem, and a settable wire positioned in said hem capable of being bent at any time to present different configurations.

7. A glove of the character described, including a hand merging into fingers and a thumb at one part and into a cuff or gauntlet at another part, the glove at the wrist portion being provided with folded portions and lines of stitching for holding the folded portions in position, said folded portions presenting a plurality of tunnels, a settable member positioned within each of said tunnels, said settable members being adapted to be bent over to constrict the glove at the wrist portion after the glove has been placed upon the hand, whereby a slenderizing effect is produced.

8. A glove of the character described, including a glove structure formed with a plurality of tunnels at the wrist portion, and a settable structure positioned in each of said tunnels, said settable structures being adapted to be bent over to constrict the glove at the wrist portion so that the glove will present a tapering structure at each direction from the wrist portion.

PAUL A. CHANUT.
